The ornamental design for folding sawhorse, as shown and described.

DESCRIPTION

FIG. 1 is a perspective view of a folding sawhorse of my design;

FIG. 2 is a right side view of the folding sawhorse of FIG. 1, the left side view being the same;

FIG. 3 is an end view of the folding sawhorse;

FIG. 4 is a plan view of the folding sawhorse;

FIG. 5 is a bottom view of the folding sawhorse; and, FIG. 6 is a perspective view of my folding sawhorse design in its folded position.
